US0D1068647S

(12) **United States Design Patent** (10) Patent No.: **US D1,068,647 S**
(45) Date of Patent: ** Apr. 1, 2025

(54) **BATTERY**

(71) Applicant: **Boundless Mobility Limited**, London (GB)

(72) Inventors: **Daniel John Barnes**, London (GB); **Andrew Pawson**, London (GB); **Arthur Blake**, London (GB)

(73) Assignee: **Boundless Mobility Limited**, London (GB)

(**) Term: **15 Years**

(21) Appl. No.: **29/870,723**

(22) Filed: **Feb. 2, 2023**

(30) **Foreign Application Priority Data**

Aug. 9, 2022 (EM) 009143258-0001
